UNITED STATES PATENT OFFICE.

HANS SIEGWART, OF LUCERNE, SWITZERLAND.

PROCESS AND APPARATUS FOR MANUFACTURING TUBULAR BODIES FROM CONCRETE.

Application filed April 11, 1924. Serial No. 705,853.

To all whom it may concern:

Be it known that I, HANS SIEGWART, a citizen of the Republic of Switzerland, residing at Lucerne, Switzerland, have invented certain new and useful Improvements in a Process and Apparatus for Manufacturing Tubular Bodies from Concrete, of which the following is a specification, reference being had therein to the accompanying drawing.

The invention relates to improvements in a process and apparatus for manufacturing tubular bodies such as hollow piles, conduits, pipes, masts and the like from concrete and particularly pipes from reinforced concrete in which the plastic concrete mass is helically wound in strips around a core and pressed on the latter by means of a band. According to the present improved process strips of concrete of a smaller width than the width of the band are helically applied to the core so that each coil of the strip is pressed consecutively several times during the same working stage. This process is of particular advantage when manufacturing pipes of reinforced concrete as the strips which are several times compressed are already in the first stage of operation so hard that the reinforcing wires will no longer cut into the strips and may be wound on the latter during this first stage. Preferably the band is so guided that it is pressed only against a part of the circumference of the rotating core. Further provision may be made that by feeding an endless band in an oblique direction on and off the core parts of the apparatus supporting the band are displaced parallel to the core.

The invention will be more fully explained with reference to the accompanying drawings on which a constructional example of the apparatus and a concrete pipe in the various stages of manufacture are diagrammatically illustrated.

Fig. 1 shows the apparatus in side elevation.

Fig. 2 is a plan view.

Fig. 3 is an end view of the apparatus.

Fig. 4 is a section along line A—B of Fig. 1.

Fig. 5 is an end view of the apparatus seen in the direction of the arrow in Fig. 1.

Fig. 6 shows a detail in section, and

Fig. 7 is a plan view of this detail.

Fig. 8 shows diagrammatically the man-

ner in which the band is slung around the core.

Figs. 9-14 show diagrammatically a concrete pipe in various stages of its manufacture.

Referring now to the drawings, 1 is the core pattern which may consist of a tube of sheet-iron the diameter of which may be altered in a known manner. Disks 2 project into the core and the diameter of these disks may be altered in a known manner so that the disks may be pressed tightly against the inner circumference of the tubular core 1. The disks 2 are rotatably mounted on axles 3, (Fig. 3), the latter being mounted in standards 4 and adapted to be displaced in the axial direction by means of the screw threaded spindles 5 and hand wheels 6. This arrangement with which the means for supporting the core project into the interior of the core presents the advantage that the core, the weight of which is comparatively low, is better protected against deflection than it is the case with the hitherto known arrangements for supporting the core. The standards 4 are stationary so that the core 1 may rotate but is secured against axial displacement. Between the two stationary standards 4 a carriage 9 resting with wheels 8 on rails 7 is adapted to travel in a direction parallel to the core 1. The carriage is provided with two tubes 10 and 11 co-axially arranged and rotatably mounted in traverses 12 of the carriage. On each of the tubes 10 and 11 a standard 13 is displaceable in the axial direction of the tubes but is secured against rotation relatively to the tubes 10 or 11 respectively. Each standard 13 supports a press roller 14 which may be displaced and adjusted into oblique positions by turning the hand wheels 70, 71 and 72, the press rollers 14 are adapted to bear against opposite sides of the core. The pressure by which the rollers 14 are urged against the core is caused by the compression springs 15, and the spring power may be adjusted by means of the hand wheels 16 according to the size of the diameter of the core 1.

The standard 13 shown on the left hand side of Fig. 1 is further provided with brackets for supporting the guide rollers 17, 18 and further rollers 20, 21, 22 carrying the reinforcing wire 23, the rollers 20, 21, 22 are preferably provided with brakes so that the reinforcing wire may be wound off

these rollers under tension. The standard 13 shown on the right hand side of Fig. 1 supports the guide rollers 24 and 25.

Upon the left hand end of tube 10 a driving roller 33 is mounted driven by the motor 73 through the interposition of a worm gear 74. The roller 33 serves for driving a comparatively wide endless band 34 which passes through the interior of the tubes 10 and 11 over a roller 31, a tightening roller 30 and guide rollers 27, 25 and 24, whereupon it is slung around the underside of the core 1 (Fig. 8) and runs over the rollers 18, 17 and 35 to the driving roller 33. The lower part of the band 34 which runs inside the tubes 10 and 11 is thus protected. The tightening roller 30 is mounted in bearings moving in a slot 28 and is displaced along said slot by a hand wheel 29 co-operating with a screw threaded spindle 29' for the purpose of adjusting the tightening of the band. On the adjacent ends of the tubes 10 and 11 levers 36 and 37 are fixed. The outer ends of the levers are provided with toothed segments 39 with which a pinion 40 (Fig. 4) co-operates. The pinion 40 is connected by its shaft with a worm wheel 41 which is in mesh with a worm 42. The latter (Fig. 1) is fixed to a shaft 43 that may be rotated by the hand wheel 44. When the hand wheel 44 is turned, the tubes 10 and 11 are turned in opposite directions through the same amount and thereby the standards 13 are swung out of their vertical position.

In order to distance the standards 13 from each other to correspond to the diameter of the core 1 to the sleeve parts of the standards 13 surrounding the tubes 10 and 11 respectively racks 45 and 46 respectively are linked, which operate with the lower and the upper teeth respectively of a pinion 47. The latter is rigidly connected to a worm wheel 48 with which a worm mounted on a shaft 49 co-operates, a hand wheel 50 serves to turn the shaft 49. When the hand wheel 50 is turned in one or the other direction the standards 13 are brought nearer to each other or are moved away from each other. 51 denotes a container from which concrete is fed to the band 34. The width of the concrete strips are adjusted by regulating the quantity of concrete fed from the container to the band or by causing the concrete on the band to pass scraping devices of any known type arranged near the guide roller 25 or controlling the outlet from the container.

As the concrete strip wound helically around the core has a smaller width than the band 34, provision is made that the concrete, which is pressed by means of the band 34 and the press rollers 14 against the core 1, does not get squeezed out of the band at that side on which the concrete does not bear against concrete material previously pressed

to the core. To this end the band 34 may be provided with a flexible edge, adapted to be turned up by means of two small rollers 52 (Fig. 1) or to both sides of the rollers 14 segments 53 (Figs. 6 and 7) may be arranged. The small rollers or the segments are preferably displaceably arranged in the direction towards the core 1. The segments 53, for instance, are connected to a two-armed lever 54, mounted upon an axle 55. The latter may be turned somewhat by the action of a worm gear 56 and a hand wheel 57, whereby either one or the other segment is moved to bear against the core 1. This obturation is only required on one side of the band 34, which side depends on the direction of rotation of the machine.

The process is carried into effect by means of the above described machine in the following manner:

The tubular core 1 is provided with end rings 58 projecting above its circumference and is then mounted in the supporting disks 2 in the position illustrated in Fig. 3. The standards 13 are placed in their upright position, in which case the band 34 moves at right angles to the axis of the core. The carriage supporting the standards is so adjusted along the core that the band bears on one side against the ring 58. Thereupon the drive for the band 34 is cut in and the band is suitably tightened by operating the hand-wheel 29. The standards 13 are so far approached towards the core 1 by turning the hand wheel 50 that the rollers 14 press against the band 34. This pressure is regulated by means of the hand wheels 16. Then concrete in a plastic condition is fed from the container 51 to the band 34, the latter conveying the material towards the left in the direction of the arrow indicated in Fig. 1 over the roller 24. From the latter the concrete material falls down upon the core and is pressed by the rollers 14 and the band 34 to the circumference of the core. At the beginning the supply of the concrete is so adjusted that the material is applied in a strip having the same width as the band 34, the roller 52 on one side or the slide 53 on the other side preventing the material from being squeezed out laterally of the band 34. In this manner a concentric ring 59 of concrete (Fig. 9) is formed. Thereupon the standards 13 are brought into oblique positions, one of the standards being inclined to one side and the other standard to the other side of the vertical and the press rollers 14 are also adjusted into correspondingly inclined positions, so that the rollers bear snugly against the layer of concrete. The supply of concrete is then continuously regulated from a smaller supply to a larger supply so that a wedge shaped strip 60 (Fig. 10) is supplied, the width of which increases to the determined width x (Fig. 11), which

corresponds, for instance, to one third of the width of the band 34. From this moment onwards the supply of concrete is so regulated that helical strips of the width a are deposited one aside the other and are strongly pressed to the core 1. Therefore while the band 34 (Fig. 12) holds a fresh helical strip on the core and the rollers 14 press this strip tightly on the core and compress it; the band and the rollers exert at the same time a repeated pressure on the strips b and c previously brought into position. In this manner it is possible to wind the reinforcing wires 23 under tension already during the first stage of manufacturing the pipe, either below the band 34 or behind the band on the concrete ring without having to fear that the wire will cut into the material as the latter has been repeatedly compressed. The above mentioned process is continued until after almost the whole core is covered with the helical strips. Then a straight winding of material must be joined onto the helical winding. The wedge shaped portion 62 at the end of the helically wound tube is produced in the opposite manner to that in which the wedge shaped strip 60 at the beginning of the tube has been obtained, i. e., by a gradual reduction of the supply of concrete.

With the hitherto known machines this operation has required much time, in fact, it had to be performed in three successive stages of operation. In the known first stage the material had been wound upon the core and had to be held thereto by means of a jute band wound around the material on the whole length of the tube. During a second stage of operation the windings of the material, while have passed the press rollers only once, had to be acted upon by the press rollers a second time, and only during a third stage the jute band could be removed and the reinforcements be wound upon the material.

Furthermore with the hitherto known machines of a similar type no provision was made to finish the ends of the pipes by rings placed at right angles to the axis of the tube as these machines applied the material only in continuous spirals.

In case a muff has to be provided at the end of the tube, as is shown in Fig. 14, to the shell of the tube first of all a cylindrical shoulder piece 63 is formed. Thereupon an angle iron ring 64 is mounted upon the concrete shell 61 and a mould 65 for the muff is mounted upon the core 1. Then the cylindrical layer 66 forming the flange of the muff is deposited by means of the band 34.

The band 34 running in an oblique direction causes a displacement of the carriage 9 on the rails 7 relatively to the core so that there is no special driving agent necessary for effecting this displacement.

When the first layer of material has been completed the standards 13 are inclined to the opposite sides whereby the movement of the carriage 9 is reversed and a further layer of concrete and simultaneously reinforcing wires may be deposited on the first layer. In the same manner as the first and second layer of material any number of further layers may be deposited until the desired thickness of the shell of the tube is obtained. When this is the case the diameter of the disks 2 is reduced so that the latter may be removed from the core 1 and the latter is removed from the finished tube. The core 1 may thus be used again.

I claim:

1. In an apparatus for manufacturing tubular bodies such as pipes, masts and the like from concrete and reinforced concrete, a turnable core, a moving band slung around parts of said core and effecting the application of the concrete on the core, and means carrying guide rollers for said band and adapted to be angularly adjusted in opposite directions about an axis at right angles to the axis of the core.

2. In an apparatus for manufacturing tubular bodies such as pipes, masts and the like from concrete and reinforced concrete, a turnable core, a moving band slung around parts of said core and effecting the application of the concrete on the core, a carriage, standards arranged on said carriage to each side of the core, supporting guide rollers for said band, and means for angularly adjusting said standards in opposite directions about an axis at right angles to the axis of the core.

3. In an apparatus for manufacturing tubular bodies such as pipes, masts and the like from concrete and reinforced concrete, a turnable core, a moving band slung around parts of said core and effecting the application of the concrete on the core, a carriage adapted to move parallel to the axis of the core, two coaxial tubular members rotatably mounted on said carriage, standards connected to each of said tubular members and supporting guide rollers for said band, and means adapted to turn said tubular members simultaneously in opposite directions through the same angle.

4. In an apparatus for manufacturing tubular bodies such as pipes, masts and the like from concrete and reinforced concrete, a tubular core, a moving band slung around bands of said core and effecting the application of the concrete on the core, a carriage adapted to move parallel to the axis of the core, two coaxial tubular members rotatably mounted on said carriage, a standard movable along each tubular member but secured against turning relatively to its tubular member and supporting guide rollers for said band, means adapted to

- cause a displacement of said two standards along said tubular members by equal amounts, and means adapted to turn said tubular members simultaneously in opposite directions through the same angles.
5. In an apparatus for manufacturing tubular bodies such as pipes, masts and the like from concrete and reinforced concrete, a turnable core, an endless moving band slung around parts of said core and effecting the application of the concrete on the core, a carriage adapted to move parallel to the axis of the core, two coaxial tubular members rotatably mounted on said carriage, standards connected to each of said tubular members and supporting guide rollers for said band, the lower part of said band passing through said tubular members, and means adapted to turn said tubular members simultaneously in opposite directions through the same angle.
6. In an apparatus for manufacturing tubular bodies such as pipes, masts and the like from concrete and reinforced concrete, a hollow core, turnably mounted means projecting into and in engagement with the interior of the core for rotatably supporting the core, a moving band slung around parts of said core and effecting the application of the concrete on the core, and means carrying guide rollers for said band adapted to be angularly adjusted in opposite directions about an axis at right angles to the axis of the core.
35. 7. In an apparatus for manufacturing tubular bodies such as pipes, masts and the like from concrete and reinforced concrete, a turnable core, a moving band slung around parts of said core and effecting the application of the concrete on the core, adjustable means adapted to prevent the plastic concrete to be squeezed out laterally of the band, and means carrying guide rollers for said band and adapted to be angularly adjusted in opposite directions about an axis at right angles to the axis of the core.
8. In the making of tubular bodies of concrete by means of an endless band cooperating with a rotatable form, the process which comprises supplying the concrete to said band only over a portion of the width of the band and confining the concrete at one side during its application to the form, and exerting a pressure on the concrete in addition to the pressure exerted by the band.

9. In the making of tubular bodies of concrete by means of an endless band cooperating with a rotatable form, the process which comprises supplying the concrete to said band only over a portion of its width, spirally applying the concrete to the form while confining the concrete at one side at points where the band runs onto and off the form and exerting at such points a pressure on the concrete in addition to the pressure exerted by said band.

10. In an apparatus for making tubular bodies, a turnable core, a concrete applying band arranged to move substantially horizontally toward the core, pass beneath the core and around a portion thereof then upward and horizontally away from the core thus leaving the top of the core exposed, means to change the angular relation of core and band, and pressure rollers acting on said band where it applies concrete to the core and at the running off point.

11. In an apparatus for making tubular bodies of concrete, a turnable core, a moving concrete applying band slung around the lower portion of the core, lateral concrete confining means at the running on and running off portions of the band, and devices to adjust said means to cause them to act on the outer side of the concrete strip at such portions.

12. In an apparatus for making tubular bodies of concrete, means for turnably supporting a core, a carriage movable along the core, an endless concrete applying band, a standard on said carriage on each side of the core having supporting and guiding means for said band, and means to simultaneously and oppositely rotate said standard on an axis perpendicular to the axis of the core.

13. In an apparatus for making tubular bodies of concrete, means for turnably supporting a core, a carriage movable longitudinally of the core, an endless concrete applying band, a pair of aligned tubes mounted in said carriage and through which said band travels, standards mounted on said tubes having supporting and guiding means for said band, and means to simultaneously and oppositely rotate said tubes to incline said standards to opposite sides of said tubes when desired.

In testimony whereof I affix my signature.

HANS SIEGWART.
